C. COEN.
CONTROLLABLE TORCH.
APPLICATION FILED JUNE 14, 1920.

Patented May 10, 1921.

UNITED STATES PATENT OFFICE.

CASTLEMAN COEN, OF SAN FRANCISCO, CALIFORNIA.

CONTROLLABLE TORCH.

1,377,875.

Specification of Letters Patent. Patented May 10, 1921.

Application filed June 14, 1920. Serial No. 388,807.

To all whom it may concern:

Be it known that I, CASTLEMAN COEN, citizen of the United States, residing at San Francisco, in the county of San Francisco 5 and State of California, have invented certain new and useful Improvements in Controllable Torches, of which the following is a specification.

The present invention relates to an improved torch for igniting the burners discharging into oil burning furnaces, and is more particularly adapted for use in connection with the ignition of the burners situated beneath or in the boilers located on 10 vessels, or in such places wherein a multiple or series of boilers are employed in fire-rooms, although the use of this invention is not so restricted, inasmuch as the same is adapted for the ignition or lighting of fires 15 generally.

In its preferred embodiment, the torch constituting the present invention comprises a suitable tubular handle on which is mounted for longitudinal and rotatable movement 20 a slideable barrel, which barrel at one end carries, or has united thereto, a snuffer shell adapted on one movement of the barrel to snuff out the flame of the torch; the tubular handle at its opposite end carrying a holding reservoir or magazine adapted to contain a quantity or supply of the hydrocarbon fuel employed for the saturation of waste or body of absorbent material carried at the lower extremity of the tubular handle. 25

The object of the invention is to provide a simple, efficient, inexpensive, and durable torch for the purposes desired, and one wherein by the use thereof the fire risk incident to the lighting of fires is reduced to a 30 minimum.

In order to comprehend the invention, reference should be had to the accompanying sheet of drawings, wherein—

Figure 1 is a perspective view of the torch illustrating the snuffer in raised position for exposing the body of waste or saturated absorbent material to be ignited.

Fig. 2 is a broken longitudinal sectional view of the torch, illustrating the snuffer in 40 closed or lowered position and the valve for controlling the flow of the liquid hydrocarbon to the body of waste or absorbent material in open position, the tubular handle on which the barrel or shell carrying the 45 snuffer and the liquid holding reservoir is mounted for movement being non-sectioned.

Fig. 3 is a plan sectional view taken on line 3—3, Fig. 2 of the drawings, and viewed in the direction of the arrows.

Fig. 4 is a detail view of the controlling 60 valve and its stem.

In the drawings, the numeral 1 is used to designate a cylindrical handle preferably formed hollow and which carries at its upper 65 end a liquid holding magazine or reservoir 2. At its lower end portion the said handle is perforated and closed by an enlarged head 3, and the said handle is also provided adjacent its lower end with a flanged collar 4. That portion of the tube intermediate the 70 flanged collar 4 and the head 3 is wrapped or covered with a pad of absorbent material 4', as, for instance, waste or asbestos, which receives for saturation through the openings or perforations 5 formed in the lower 75 end portion of the handle a supply of hydrocarbon mixture, such, for instance, as kerosene, which is delivered thereto through the hollow tubular handle from the liquid holding reservoir or magazine 2 carried at the 80 upper end of the said handle. On the handle 1 is mounted for longitudinal and rotatable movement a sleeve or barrel 6, which sleeve or barrel at its lower end carries an enlarged cylindrical shell 7 which serves the function 85 of a snuffer on the lowering movement of the shell or barrel for the snuffing out of the flame of the torch, the said shell or snuffer being of such diameter as to completely inclose or house the body of absorbent material 4' when the sleeve or barrel is in its 90 lowermost position. The said barrel or shell is provided with a longitudinally disposed slot 8, which at one end terminates in an angularly disposed notched extension 9, and 95 at its opposite end in a similar notched extension 10, the two notched end extensions 9—10 being projected from opposite sides of the slotted section 8 of the said sleeve or barrel 6. A projecting headed retaining 100 guide stud 11 is secured to the handle 1 of the torch, said stud projecting through the slotted section of the barrel or sleeve 6 and serving to maintain the same in position relative to the handle 1.

The holding reservoir or magazine 2 is connected or united to the upper end of the tubular holder 1 of the torch by means of the threaded coupling 12, which interiorly is provided with a valve seat 13 which is 110 opened or closed by means of a valve 14, said valve being held normally in closed posi-

sition by means of the tension spring 15 situated within the said coupling. The stem 16 of the valve is a part hollow one, and its tubular portion is provided with two spaced 5 air ports 17 and 17'. This stem projects through a removable cap 18 for the liquid holding reservoir or magazine 2, and this cap in turn is provided with air ports 18'. When the valve stem is depressed to cause 10 an unseating of the valve, the upper air port 17' of the stem 16 is brought into registry with the ports 18' of the cap 18, thereby admitting air to the interior of the valve stem, which escapes therefrom under atmospheric 15 pressure through the lower port 17, and into the interior of the holding reservoir or magazine 2 and supplies the requisite air pressure for causing the feeding of the hydrocarbon liquid from within the holding reservoir or magazine to the tubular 20 holder of the torch, through which the same flows and escapes therefrom through lower perforations 5 for the saturation of the body of absorbent material 4' secured to the 25 lower end thereof.

When the body of absorbent material has been sufficiently saturated with the liquid hydrocarbon, the same is lighted and provides a large flame for igniting the hydro- 30 carbon mixture flowing from the oil or burner beneath the boilers, or for the lighting of fires generally.

The invention is designed more essentially to take the place of the crude form of 35 torches at present employed for the firing of oil burners, and which consists essentially of a handle of sufficient length, to one end of which is applied a body of waste or absorbent material, which is saturated by being dipped into a body of liquid hydrocarbon. In connection with such form of 40 torches, no means are provided for snuffing out the flame after the burners have been ignited, the usual resort being, when it is 45 desired to extinguish the torch flame, to dip the same for quenching purposes into the body of hydrocarbon. This, at best is a crude manner for lighting the burners beneath a boiler, inasmuch as necessarily, 50 as the torch after being dipped into the body of hydrocarbon is carried a distance prior to being lighted, there is a drip of the hydrocarbon over the floors, and there is always the liability when the flame is extinguished of setting fire to the body of the liquid hydrocarbon. It will thus be seen 55 that the fire risk is somewhat heavy.

By the utilization of the present invention, all fire risks are eliminated, and the 60 feed of the hydrocarbon to the waste or absorbent head of the torch is absolutely under control of the operator and equally so the extinguishing or snuffing of the flame. When the flame of the torch has been 65 snuffed out, the sleeve or barrel will be in

its lowermost position and on giving a part rotation thereto, the stud 11 secured to the tubular handle of the torch enters within the radial slotted extension 10, and secures the parts in lowered position.

When it is desired to use the torch, the barrel or sleeve 6 is given a part rotation to take the stud 11 from within the said slotted extension 10, which permits of the sleeve or barrel being moved longitudinally 75 upwardly its full distance, when a part rotation is given thereto to place the projecting stud within the upper radial slotted extension 9, so as to hold said sleeve, barrel or shell 6 in its open position relative to 80 the absorbent head of the torch.

While the invention has been described in its preferred embodiment, I do not wish to be understood as limiting or confining the same to the detailed construction of the working parts shown and described, but on the contrary wish to be understood as claiming the invention as broadly and for all purposes as the state of the art will warrant.

It will be understood that the torch may 90 be made in various sizes, so that its use is not limited to the lighting of burners beneath boilers, but the same may be of such size to be used in connection with the lighting of fires in houses.

Having thus described the invention what is claimed as new and desired to be protected by Letters Patent is:—

1. A controllable torch for the described purpose, the same comprising a handle provided at one end with a body of absorbent material, a holding reservoir at the other end and adapted to contain a body of hydrocarbon mixture through the handle, means for controlling the flow of liquid from the holding reservoir to the body of absorbent material, and means permanently mounted on the handle capable of outward longitudinal movement thereon for snuffing out the flame of the torch.

2. A controllable torch for the described purpose, the same comprising a tubular handle provided adjacent one end with a series of perforations, a body of absorbent material inclosing said perforated section of the handle, a reservoir at the other end of the handle adapted to contain a body of liquid hydrocarbon, a sleeve mounted on the handle between the reservoir and body of absorbent material for longitudinal and rotatable movement and provided at its lower end with an enlarged shell adapted to inclose the body of absorbent material when the same is in lowered position to snuff out the flame of the torch, and means for controlling the flow of liquid from within the reservoir to the said body of absorbent material.

3. A controllable torch for the described purpose, the same comprising a handle carrying at one end a body of absorbent ma-

- terial and provided with controllable means, a valve capable of operation for admitting air into the reservoir and the escape of the liquid hydrocarbon therefrom at 5 a point removed from the air inlet port and for separating the absorbent material for regulating the flow of liquid hydrocarbon thereto, and means carried by the handle for snuffing out the flame of the 10 torch.
4. A torch for the described purpose, the same comprising a tubular handle perforated adjacent one end thereof with a body of absorbent material covering said perforated section of the handle, a reservoir 15 adapted for the holding of a body of liquid hydrocarbon associated with the handle, a valve for controlling the flow of hydrocarbon from the reservoir to the body of absorbent material, means for actuating said 20 valve, and snuffer means carried by the handle for extinguishing the flame of the torch.
5. A torch comprising a tubular handle, a wick at one end thereof, a reservoir at the 25 other end for containing liquid hydrocarbon for supplying to the wick through the handle, a valve for controlling the flow of liquid hydrocarbon from the reservoir to the 30 wick, a tubular stem associated with the valve for operating the same, said stem adapted for providing a connection from the atmosphere to the interior of said reservoir on the opening of said valve.
- 35 6. A torch comprising a tubular handle, a wick at one end thereof, a liquid hydrocarbon containing reservoir at the other end thereof for supplying liquid hydrocarbon
- thereto through said handle and a normally closed valve mechanism for controlling the 40 passage of liquid hydrocarbon from the reservoir, said valve when open providing an air vent from the atmosphere into the reservoir at a point removed from the passage of the liquid hydrocarbon from the 45 reservoir.
7. A torch comprising a tubular handle carrying at one end a wick, a reservoir at the other end of the handle for containing liquid hydrocarbon for supplying to the 50 wick, a snuffer for enveloping the wick, a sleeve mounting the snuffer and slidably on said tubular handle between said wick and reservoir, a pressure actuated valve for controlling the supply of fuel from the reservoir to the wick, and a spring for normally closing said valve on the release of pressure therefrom.
8. A torch comprising a tubular handle, a wick at one end thereof, a reservoir at the 55 opposite end thereof for containing liquid hydrocarbon for supplying through the handle to said wick, means for controlling the flow of hydrocarbon from the reservoir to the wick, a snuffer carried by the 60 handle between the reservoir and wick and adapted to normally overlie and conceal said wick, said snuffer adapted for inward movement on the handle to expose the wick and means for locking the snuffer at 65 the end of its movement in either direction on said handle.

In testimony whereof I have signed my name to this specification.

CASTLEMAN COEN.
